United States Patent Office

Des. 216,285
Patented Dec. 9, 1969

216,285

PORTABLE X-RAY MACHINE

Kuniyoshi Shiiba, Tokyo, Japan, assignor to Kramex
Corp., New York, N.Y., a corporation of New York

Filed June 25, 1968, Ser. No. 12,498

Term of patent 14 years

Int. Cl. D24—02; D16—01
U.S. Cl. D83—1

FIG. 1

FIG. 3

FIG. 2

FIG. 4

FIG. 5

FIG. 6

FIG. 1 is a front elevational view of a portable X-ray machine embodying my new design;

FIG. 2 is a right side elevational view thereof;

FIG. 3 is a left side elevational view thereof;

FIG. 4 is a rear elevational view thereof;

FIG. 5 is a top plan view thereof; and

FIG. 6 is a bottom plan view thereof.

I claim:

The ornamental design for a portable X-ray machine, as shown.
